CLAIM

The ornamental design for a wearable electronic device, as shown and described.

DESCRIPTION

FIG. 1 is a front perspective view of a wearable electronic device showing our new design;

FIG. 2 is a front view thereof;

FIG. 3 is a top view thereof;

FIG. 4 is a bottom view thereof;

FIG. 5 is a rear view thereof;

FIG. 6 is a left side view thereof; and,

FIG. 7 is a right side view thereof.

The dashed broken lines shown in the drawings depict portions of the wearable electronic device that form no part of the claimed design.

1 Claim, 6 Drawing Sheets
